DOOR OPENING AND CLOSING MECHANISM
FOR ELEVATORS

Harold C. Crane, Toronto, Ontario, Canada, assignor to Turnbull Elevator Company Limited, Toronto, Ontario, Canada

Application March 2, 1939, Serial No. 259,483
In Canada February 11, 1939

5 Claims. (Cl. 187—56)

This invention relates to door opening and closing mechanism for elevators of the type in which mechanism carried by the car door is utilized to simultaneously open the hatchway door when the car door is opened, and more particularly to a construction in which the hatchway door is normally held closed by a toggle lever.

My object is to unlock the hatchway door by breaking the toggle and then lock it tightly without slack to the car door.

I attain my objects by means of the constructions hereinafter described, and illustrated in the accompanying drawings in which

15 Fig. 1 is a front elevation of the mechanism on the car door;

Fig. 2 a section on the line 2—2 in Fig. 1, showing also part of the co-operating mechanism of the hatchway door;

20 Fig. 3 a side elevation of the hatchway door mechanism with the door removed; and

Fig. 4 a diagrammatic front elevation of part of the car door mechanism.

The car is illustrated as slidably mounted in 25 a shaft on guide rails 28 on the shaft wall 27. Although two co-operating doors may, and usually are used, for the sake of simplicity a single sliding car door 5 is shown which in its closed position meets the fixed wall 26 of the car.

30 On the car is mounted the main door operating lever 1 which is pivotally connected to the bottom car supporting beam 29 and is operated in the ordinary way and which is connected to operate a slide 2 which carries a movable clutch member 6 adapted to co-operate with a clutch member 9 fixed to the car door 5 and which 35 clutches are adapted to engage two rubber rollers 7 and 8 pivoted on the hatchway door 25 one over the other. One of these rollers is fixed

40 relative to the hatchway door 25 but the other one is so arranged that it has a travel of about an inch and a half, this travel being utilized to pick up the hall door without shock and at the same time break the toggle 15 holding the door

45 closed. After the toggle has been broken these two rollers are vertically in line and are squeezed by the clutch mechanism of the car door. The main door operating lever 1 directly operates the slide 2 carrying the movable clutch 6 and is indirectly connected with the car door by the following mechanism:

An arm 10 is rigidly secured to and extends laterally from the upper end of the main door operating lever, which arm is connected by means of a link 11 with an upwardly extending

L-shaped lever 12 pivoted at its lower end at 13 on the car door and having a rod A pivotally connected with its upper end, which rod A extends through a lug C secured to the car door. On this rod is threaded a nut B which bears 5 against the side of the lug and provides an adjustable abutment determining the position of the lever system relative to the slide and the position of the movable clutch relative to the fixed clutch. A spring B bears against the opposite side of the lug and a collar E is threaded on the end of the rod A and serves to permit the door to travel slightly ahead of the door opening lever system at a point in its opening and closing movement, for a purpose hereinafter 15 explained.

The connection between the main lever 1 and the slide is necessarily arranged to allow for the arc-like movement of the main lever. Referring particularly to Fig. 1, it will be noted that the 20 upper end of this lever is secured to the slide 2 by means of a device 3 which comprises an arm 3^a pivotally connected to the lever 1 and adjustably secured to a pin 3^b which is slidably mounted in a bracket 3^c which is secured to the 25 slide 2. The slide 2 is slidably mounted in brackets 4, 4 so that when the lever 1 is moved to the right to open the car door the slide 2 slides in the brackets 4, 4, which are mounted on the outer side of the door 5 of the elevator. 30

Mounted at one end of the slide 2 is the clutch member 6 so that it moves with the slide. This clutch is pivoted on a vertical axis on a bracket 14 which is bolted to the slide 2. The clutch is in the form of a rectangular plate with an 35 inwardly turned engaging end and its upper and lower edges are bevelled so that the clutch member may swing in when the bevelled edges meet any obstruction, thus avoiding breakage. A further purpose for providing that this clutch 40 will swing in is that it may be manually moved out of the way to permit the car door to be moved relative to the hall door if it is desired to get at the mechanism for adjustment or repairs. A second or fixed clutch 9 of similar construction 45 is also provided. This is mounted on a bracket 15 which is bolted to the car door and is mounted to swing in the same manner as the clutch 6. The clutch members 6 and 9 are of considerable length to ensure their satisfactorily passing up 50 on either side of the rollers 7 and 8 into proper position for the opening operation, and are normally pressed out by springs 6^a and 9^a.

The rollers 7 and 8 hereinbefore referred to 55 which are mounted on a plate 25^a on the hall

or hatchway door 25 and the other mechanism for the operation of the hall door are arranged as follows: Referring particularly to Fig. 3, it will be understood that the roller 8 is fixedly 5 mounted on the hall door facing the mechanism on the car door. Similarly positioned is the roller 7 which is secured to the arm 21 pivoted on the hall door at 22 and adapted to engage an adjustable back stop 23. This stop 23 will usually be adjusted to position the roller with its center about $1\frac{1}{4}$ " to the left of the center of the roller 8.

The cam arm 19 is pivoted at one end to the toggle lever 15 at 18 and at the other end to the 15 adjustable toggle lock arm 20 which is also pivoted to the toggle and which serves to adjust the position of the cam arm 19 relative to the arm 21. The toggle lever 15 is pivotally connected at 17 to the wall 27 of the elevator shaft and at 20 18 to the hall door and is pivoted centrally at 16 where it may be broken initially by pressure applied to the toggle lock arm by the arm 21 through the medium of the cam arm 19.

An adjustable stop 24 prevents the toggle 25 breaking downwardly.

The mode of operation is substantially as follows: With the lever 1 in the position shown in Figs. 1 and 2 of the drawings, the car door and the hall door are entirely closed. The first movement of the lever 1 to the right, as viewed in the drawings, moves the slide 2 and with it the clutch member 6 connected thereto. The door at first moves at a relatively slower speed than the end of the lever 1 which first swings the arm 10 upwardly and rocks the link 11 and lever 12, moving the lever 12 and rod A in the direction of travel of the lever 1, but at a slower speed, and causing the car door which is slidably mounted on the elevator, to move by engagement of the 30 nut B with the lug C. Continued swing of the lever 1 to the right, however, straightens out the link 11 and ultimately brings it into alignment with the direction of movement of the lever 1, causing it to pull the lever 12, the rod A, and the 40 door at substantially the same speed as the upper end of the lever 1.

During the initial movement of the lever 1 to the right, the slide 2, which is directly connected to the lever 1, moves to the right more rapidly 50 than the car door, causing the clutch 6 to engage the roller 7, move it into alignment with the roller 8 and clamp them against the clutch 9, thus breaking the toggle 15 on the hatchway door as previously described. After the rollers 55 have been so clamped, the clutch 6 and the car door travel at substantially the same speed so that the relative positions of the clutch 6 and the clutch 9, which is secured to the car door, are maintained for the greater part of the forward and backward movements.

It has been said that, after its initial movement, the clutch 6 during the opening and closing movement of the door travels at substantially the same speed as the car door and the clutch 65 9, holding the rollers 7 and 8 clamped tightly together, and thus positively locking the car and hatchway doors together without backlash. However, owing to the relative arrangement of the mechanism operating the clutch 6 and the car door (and clutch 9) respectively, during the greater part of the forward and backward movement the clutch 6 travels a little ahead of the car door. In Fig. 1 there is shown in dotted lines the approximate relative positions of the various 70 parts of car door operating mechanism after the 75

lever has been moved to the right. This shows that the car door does not maintain the same relative position to the clutch 6 as it had at the commencement of the opening movement. There is, in fact a definite lag. This would ordinarily develop excessive pressure on the rollers 7 and 8, which would cause the mechanism to jam or break. To relieve such pressure, the spring D, described above, is provided. This spring permits the car door to run ahead of the car door 10 operating mechanism 1, 16, 11, 12 and A, while at the same time exerting sufficient retarding pressure to retain the clutch 9 in engagement with the rollers 7 and 8 thus keeping the two doors 15 constantly positively interlocked and returning the nut B to engagement with the lug C at the latter part of the closing movement.

The return movement of the lever 1 actuates the rod A to the left, as viewed in the drawings. The compression of the spring D against the lug 20 C actuates the car door thus giving an easy start and resilient drive to the door. The clutch 6 is positively actuated in the return direction, maintaining substantially the same relationship to the clutch 9 as in the opening movement. Final 25 movement of the lever 1 to the left returns the link 11 with the parts attached thereto to the initial position with both doors closed and the clutch 6 positioned spaced from the clutch 9, permitting the hall door to be locked by the movable 30 roller 7 which takes up the position which permits the toggle arm 15 to straighten out and hold the hall door closed.

What I claim as my invention is:

1. Mechanism for opening and closing hatchway doors and car doors of elevators, comprising means for opening the car door; a clutch member; means operable by the car door opening means for moving the clutch member with but initially faster than the car door; a clutch member fixed 40 on the car door and spaced from the relatively movable clutch member; a member mounted on the hatchway door for limited movement relative thereto and normally positioned between the said clutch members when the car is at a landing; and a toggle lock arm adapted to be actuated by the relatively movable hatchway door member to break the toggle, the relatively movable clutch member during its initial relatively fast movement engaging the relatively movable hatchway door member and moving the same to cause it to actuate the toggle arm and break the toggle and clamp the said hatchway member against the fixed clutch member. 45

2. Mechanism for opening and closing hatchway doors and car doors of elevators, comprising means for opening the car door; a clutch member; means operable by the car door opening means for moving the clutch member with but initially faster than the car door; a clutch member fixed 60 on the car door and spaced from the relatively movable clutch member; a member fixed to the hatchway door; a member mounted on the hatchway door for limited movement relative thereto and normally positioned between the said clutch members when the car is at a landing; and a toggle lock arm adapted to be actuated by the relatively movable hatchway door member to break the toggle, the relatively movable clutch member during its initial relatively fast movement 65 engaging the relatively movable hatchway door member and moving the same to cause it to actuate the toggle arm and break the toggle and clamp the said fixed and relatively movable 70 member. 75

hatchway door members in vertical alignment against the fixed clutch member.

3. Mechanism for opening and closing hatchway doors and car doors of elevators, comprising a lever for operating the car door; a member slidably mounted on the car door and operated directly by the car door operating lever; a system of links and levers connecting the operating lever with the car door whereby the initial opening and final closing movement of the car door is relatively slower than the corresponding movement of the slidably mounted member; a toggle lever for locking the hatchway door; a toggle lock arm; and a swingable member mounted on the hatchway door, said member being connected to the toggle lock arm at its free end; and means whereby the slidably mounted car door member, during its initial relatively fast movement, is adapted to actuate the swingable hatchway door member to swing the same to actuate the toggle lock arm to break the toggle.

4. Mechanism for opening and closing hatchway doors and car doors of elevators, comprising a lever for operating the car door; a member slidably mounted on the car door and operated directly by the car door operating lever; a system of links and levers connecting the operating lever with the car door whereby the initial opening and final closing movement of the car door is relatively slower than the corresponding movement of the slidably mounted member; a member fixed to and movable with the car door; and a member mounted on the hatchway door and normally located between the fixed and relatively movable car door members, whereby the initial relative fast movement of the latter car door member will clamp the said hatchway door member against the fixed car door member providing a positive locking engagement between the car door and the hatchway door during all but the initial opening and final closing movement of the doors; and spring means in the lever and link system to relieve excess pressure on the hatchway door member resulting from differences in the speed of movement of the relatively movable and the fixed car door members.

cated between the fixed and relatively movable car door members, whereby the initial relative fast movement of the latter car door member will clamp the said hatchway door member against the fixed car door member providing a positive locking engagement between the car door and the hatchway door during all but the initial opening and final closing movement of the doors.

5. Mechanism for opening and closing hatchway doors and car doors of elevators, comprising a lever for operating the car door; a member slidably mounted on the car door and operated directly by the car door operating lever; a system of links and levers connecting the operating lever with the car door whereby the initial opening and final closing movement of the car door is relatively slower than the corresponding movement of the slidably mounted member; a member fixed to and movable with the car door; a member mounted on the hatchway door and normally located between the fixed and relatively movable car door members, whereby the initial relative fast movement of the latter car door member will clamp the said hatchway door member against the fixed car door member providing a positive locking engagement between the car door and the hatchway door during all but the initial opening and final closing movement of the doors; and spring means in the lever and link system to relieve excess pressure on the hatchway door member resulting from differences in the speed of movement of the relatively movable and the fixed car door members.

HAROLD C. CRANE.
